UNITED STATES PATENT OFFICE.

WILLIAM H. THOMPSON, OF EAST STROUDSBURG, PENNSYLVANIA.

HAT-FASTENER.

SPECIFICATION forming part of Letters Patent No. 450,538, dated April 14, 1891.

Application filed March 22, 1890. Serial No. 344,997. (No model.)

To all whom it may concern:

Be it known that I, WILLIAM H. THOMPSON, a citizen of the United States, residing at East Stroudsburg, in the county of Monroe and State of Pennsylvania, have invented a new and useful Hat-Fastener, of which the following is a specification.

My fastener is designed to be attached within the hat and extend around the front 10 and having at the rear downwardly and inwardly projecting spring-arms adapted to engage with the back portion of the head or hair.

In the drawings, Figure 1 is a sectional view of a hat with the fastener in place and 15 the spring-arms in the position assumed by them in use. Fig. 2 is a plan view of the fastener detached with the arms in the position when not in use. Fig. 3 is a rear view of Fig. 2, and Fig. 4 a similar view with the 20 spring-arms in their active position.

As shown in the drawings, the fastener A is formed of wire, which is bent into U shape. The fastener is attached within the hat with the rounded portion in front, and the two 25 sides extend rearwardly to near the rear side of the hat, being attached at several points throughout its extent, and thus performing functions as a strengthening or stiffening frame for the hat or bonnet. The rear ends 30 of the prongs are continued to form the spring-arms a, which extend downwardly and inwardly toward each other from the main part 1 of the fastener, the wire being bent sharply at 2 to form the spring arms. The ends of 35 the arms may be provided with any suitable ornaments. The whole fastener is springy in character, and when in place clasps the hat with easy pressure to the head. The main part of the fastener is entirely concealed, and 40 the only parts visible are the downwardly-ex-

tending spring-arms a, which clasp the head or hair at the back and have the appearance of ornamental hair-pins.

In order to attach the fastener to the hat, I provide spring-clips B, having perforated 45 base portions 3, by which the clips may be sewed to the hat, and spring-tongues 4, which extend upwardly and which clasp the wire of the fastener when pushed into engagement therewith. The fastener is thus easily removable, or it may be sewed directly to the 50 hat, though I prefer the clips as fastening means. Normally the spring-arms are in the position shown in Figs. 2 and 3; but when in use they are grasped by the hand and sprung 55 apart, as in Figs. 1 and 4, to clasp the head in rear of the ears. This action secures a torsional spring effect throughout the main portion of the fastener.

The fasteners may be attached to the hat 60 by dealers or manufacturers; or they may be sold as a separate article and attached by the individual purchaser.

I claim as my invention—

In combination with a hat, a fastener there- 65 for, consisting of a U-shaped main portion of spring-wire having spring-arms at the rear end bent inwardly from the main portion, substantially at right angles, the main portion being held within the hat at its front por- 70 tion and also supported on each side at the right-angular bends, the said spring-arms thus having downward pivotal movement from the attaching-points as centers when being applied to the head, substantially as de- 75 scribed.

WILLIAM H. THOMPSON.
